(57) **CLAIM**

I claim the ornamental design for a sewage drain tube cap,
substantially as shown.

DESCRIPTION

FIG. 1 is a top perspective view of the sewage drain tube cap
of the invention with the cap on according to Applicant's
design.

FIG. 2 is a top view of the sewage drain tube cap of the
invention with the cap on according to Applicant's design.

FIG. 3 is a bottom view of the sewage drain tube cap of the
invention with the cap on according to Applicant's design.

FIG. 4 is a left side view of the sewage drain tube cap of the
invention with the cap on according to Applicant's design.

FIG. 5 is a front side view of the sewage drain tube cap of the
invention with the cap on according to Applicant's design.

FIG. 6 is a rear side view of the sewage drain tube cap of the
invention with the cap on according to Applicant's design.

FIG. 7 is a top perspective view of the sewage drain tube cap
of the invention with the cap off according to Applicant's
design.

FIG. 8 is a bottom perspective view of the sewage drain tube
cap of the invention with the cap off according to Applicant's
design.

FIG. 9 is a top view of the sewage drain tube cap of the
invention with the cap off according to Applicant's design.

FIG. 10 is a bottom view of the sewage drain tube cap of the
invention with the cap off according to Applicant's design.

FIG. 11 is a left side view of the sewage drain tube cap of the
invention with the cap off according to Applicant's design.

FIG. 12 is a front side view of the sewage drain tube cap of the
invention with the cap off according to Applicant's design;
and,

FIG. 13 is a rear side view of the sewage drain tube cap of the
invention with the cap off according to Applicant's design.

Views of the right side of the sewage drain tube cap of the
invention with the cap on and with the cap off have been
omitted since the right side is the mirror image to the left side.
The broken lines of the figures are for the purpose of illus-
trating unclaimed portions of the sewage drain tube cap of the
invention and such broken lines form no part of the claimed
design.

1 Claim, 8 Drawing Sheets
